DESIGN FOR A REPEATER COMPASS COURSE SETTING INDICATOR

Loren J. De Lanty, Baldwin, N. Y., assignor to
Sperry Gyroscope Company, Inc., Brooklyn,
N. Y., a corporation of New York

Application October 17, 1942, Serial No. 108,552

Term of patent 7 years

To all whom it may concern:

Be it known that I, Loren J. De Lanty, a citizen of the United States of America, residing at Baldwin, in the county of Nassau and State of New York, have invented a new, original, and ornamental Design for a Repeater Compass Course Setting Indicator, of which the following is a specification, reference being had to the accompanying drawing, forming part thereof.

Fig. 1 is a front elevational view and Fig. 2 is a sectional view taken along line 2—2, in Fig. 1, of a repeater compass course setting indicator, showing my new design.

I claim:

The ornamental design for a repeater compass course setting indicator, as shown.

LOREN J. DE LANTY.
